CONTROLLING DEVICE

Roy O. Allen, Athens, Pa., assignor to Ingersoll-Rand Company, New York, N. Y., a corporation of New Jersey

Application August 27, 1943, Serial No. 500,243

4 Claims. (Cl. 121—35)

This invention relates to fluid actuated tools, and more particularly to a controlling device for a fluid actuating riveting machine of the percussive type having a mounting to slidably support the riveting machine with respect to the work.

One object of the invention is to assure uniformity of the shapes of the portions of the rivets formed by the machine.

Another object is to obviate the chances of operating the machine longer than is actually necessary to perform the work of upsetting the rivet.

Other objects will be in part obvious and in part pointed out hereinafter.

In the drawing accompanying this specification and in which similar reference numerals refer to similar parts,

Figures 1 and 2 are longitudinal elevations, partly in section, of a riveting machine embodying the invention and showing the various movable parts of the machine in different positions which they may occupy in practice.

Referring more particularly to the drawing, 20 designates a fluid actuated power unit shown as being in the form of a riveting machine, and 21 is a sample of work upon which the riveting machine may operate.

The riveting machine is arranged slidably in a casing 22 having a bracket 23 fastened thereto by bolts 24 to support the work 21. An arm 25 of the bracket 23 extends across the plane of movement of the riveting machine and contains an anvil block 26 having a recess 27 to accommodate the preformed head of a rivet 28 in the work 21.

The riveting machine 20 is of a conventional type and comprises, as casing parts, a cylinder 29 and a head block 30 threadedly connected to the cylinder. The cylinder has a piston chamber 31 and a hammer piston 32 reciprocable therein for actuating a rivet set 33 the stem of which extends slidably into the front end of the cylinder 29 to receive the blows of the hammer piston 32.

A suitable valve mechanism 34 in the cylinder and the head block serves to distribute pressure fluid to the piston chamber, such pressure fluid being conveyed to the valve mechanism by passages 35 in the head block communicating with the rearward end of the chamber or bore 36 wherein the riveting machine is slidably arranged. The piston chamber has a free exhaust port 37 intermediate its ends to communicate the piston chamber with the bore 36 forwardly of the head block 30, and in the side of the casing 22 is an

opening 38 to convey the exhaust fluid to the atmosphere.

The peripheral surface 39 of the head block 30 has a nice sliding fit on the surface of the bore 36 and a sealing ring 40 in the head block prevents the leakage of fluid along the cooperating surfaces of the head block and the bore 36. The riveting machine is additionally guided in the casing 22 by a bushing 41 in the front end of the casing to guide the forward portion of the cylinder 29, and ports 42 in the bushing 41 provide additional outlets for exhaust fluid from the front end of the bore 36. The wall of the bushing is grooved to provide a seating surface 43 for an end of a spring 44 which encircles the cylinder and seats at its other end against a flange 45 on the periphery of the cylinder 29.

The riveting machine, when idle, is held in its rearmost limiting position in the bore 36 by the spring 44 but is actuated toward the work by pressure fluid. To this end the casing is provided with a small bore 46 rearwardly of the bore 36 into which it opens and in the bore 46 is a plunger 47 having a pressure surface 48 against which pressure fluid may act for moving the riveting machine in a forwardly direction. On the opposite end of the plunger 47 is a reduced stem 49 that seats against the rearward end of the head block 30 constituting, in the construction shown, a pressure surface 50.

The pressure fluid serving to actuate the power unit and drive it forwardly in the casing 22 is introduced into the casing by a supply conduit 51 that opens into a supply passage 52 leading to the chamber 36. A valve chamber 53 intersects the supply passage 52 and from it leads a passage 54 to the rearward end of the bore 46.

The passages 52 and 54 are controlled by a rotary throttle valve 55 in the valve chamber 53, having a lever 56 for its manipulation. In the periphery of the valve 55 is a partly annular groove 57 to simultaneously afford communication between the several branches of the supply passage 52 lying on opposite sides of the valve chamber 53 and with the passage 54 in the open position of the valve 55. The valve 55 also controls the exhaust of fluid from the bore 46 and to this end is provided with a passage 58 that extends diagonally through the valve to communicate at one end with the passage 54 and at its other end with a free exhaust port 59 in the casing 22.

Means are provided to effect the automatic cut-off of pressure fluid to the chamber 36 and thus to the power unit for stopping the operation of

the latter when the work has been completed and in that way avoid the waste of power medium by continuing to deliver blows after the rivet has been suitably formed. To this end the casing 22 is provided with a valve chest 60 having a bore constituting a valve chamber 61 the outer end of which is sealed by a plug 62.

The valve chamber 61 comprises an enlarged portion 63 and a reduced portion 64 that intersects the portion of the supply passage 52 lying between the valve chamber 53 and the chamber 36. The valve chamber 61 contains a reciprocatory valve 65 comprising a head 66 that lies in the enlarged portion 63 and a stem 67 in the reduced portion 64 to control the supply passage 52. In the periphery of the stem 67 is an annular groove 68 to afford communication between the branches of the supply passage 52 lying on opposite sides of the valve chamber in a limiting position of the valve 65. The innermost end of the valve chamber 61 is preferably vented to the atmosphere through a passage 69 in the casing 22.

The valve 65 is actuated to its different controlling positions by pressure fluid and the end surface of the head 66 adjacent the stem 67 and the outer enlarged end surface of the head accordingly constitute actuating surfaces 70 and 71 against which pressure fluid acts for shifting the valve. Such pressure fluid is conveyed from the supply passage 52, at a point between the valve chambers 61 and 53, by a passage 72 that leads to a recess 73 in the valve chest 60 and has a branch passage 74 leading to the innermost end of the enlarged portion 63 of the valve chamber 61. A port 75 affords communication between the recess 73 and the valve chamber 61 for supplying pressure fluid to the actuating surface 71.

In the form of the invention shown, the flow of pressure fluid from the recess 73 through the port 75 is controlled by a throttle valve 76 of the poppet type, the head 77 of which cooperates with a tapered seating surface 78 at the juncture of the recess 73 and the port 75. A spring 79 in the recess 73 acts against the head 77 for pressing it against the seating surface 78.

The stem 80 of the throttle valve 76 extends transversely through the valve chamber 61 and through bores 81 and 82 in the valve chest 60 and the bracket 23, respectively, whereby the throttle valve 76 is held in coaxial relationship with the seating surface 78. In the stem 80 adjacent the head 77 of the throttle valve is a portion 83 of reduced diameter to permit the free flow of pressure fluid through the port 75. The portion 83 is also of such length that in the seated position of the throttle valve said portion 83 extends into the bore 82 and cooperates therewith to provide an annular space 84 for communicating the valve chamber 61 with an atmospheric exhaust port 85 in the valve chest.

The exhaust port 85 is so positioned that when the throttle valve 76 rests upon its seat it will be in free communication with the valve chamber through the annular space 84 but will be blanked off by the main body portion of the stem 80 when the throttle valve is unseated.

The force employed for unseating the throttle valve 76 is applied by the power unit 20 and is transmitted to the throttle valve by a rocker bar 86 supported by a bracket 87 on the casing 22. The rocker bar is pivotally mounted upon a pin 88 in the bracket 87 and extends with one end 89 through the opening 38 into the path of the flange 45 on the cylinder 29. The opposite end 90 of the rocker bar overlies the free end of the

valve stem 80 for engagement therewith to unseat the throttle valve 76 whenever the rocker bar 86 is tilted by the flange 45.

In the operation of the device and assuming the various parts of the machine to occupy substantially the positions shown in Figure 1, the throttle valve 55 is first rotated to establish communication between the supply passage 52 and the passage 54. Pressure fluid will then flow into the bore 46 against the pressure surface 48 and move the riveting machine 20 forwardly in the casing 22 until the rivet set 33 seats against the rivet 28.

The riveting machine will move readily in this direction without creating a sub-atmospheric pressure in the chamber 36 since the said chamber will then be in communication with the atmosphere through the passages and chambers in the riveting machine, the bore 36 adjacent the cylinder 29 and the opening 38.

After the work has been correctly positioned with respect to the rivet set the valve 55 is rotated further in the same direction until the groove 57 communicates the several branches of the supply passage 52 with each other. Pressure fluid then flows into the rearward end of the chamber 36 against the pressure surface 50 to hold the rivet set firmly against the work and to set the riveting machine 20 in operation.

In this position of the throttle valve 55 pressure fluid will then also enter the recess 73 and the inner end of the enlarged portion 63 of the valve chamber 61 and hold the valve 65 firmly in position to maintain the annular groove 68 in the valve stem in registry with the adjacent portions of the supply passage 52 so that the chamber 36 will be in free communication with the source of pressure fluid supply.

The riveting machine and the plunger 47 will then be held in the relative positions described by the pressure fluid acting against the pressure surfaces 48 and 50, and the percussive element and the pressure fluid distributing element of the riveting machine will continue operating as long as the valve 65 remains in the open position. During the upsetting of the rivet 28 the riveting machine 20 will move gradually forwardly and at about the time the rivet is suitably upset the shoulder 45 will engage the rocker bar 86 and rock it about the pivot 88.

This movement of the rocker bar will drive the end 90 thereof against the stem 80 of the throttle valve 76 and raise the head 77 from the seating surface 78. At the same time the main body portion of the valve stem 80 will overlie the exhaust port 85. Pressure fluid will then flow from the recess 73 through the port 75 into the outer end of the valve chamber 61 and shift the valve 65 inwardly thereby moving the annular groove 68 out of registry with the supply passage 52 and moving the adjacent portion of the valve stem 67 across the ends of the supply passage 52 and thus cut-off the further admission of pressure fluid into the chamber 36.

Any pressure fluid thereafter remaining in the chamber 36 will then pass through the riveting machine to the atmosphere. The riveting machine will, however, be held against the rivet by the pressure fluid acting against the actuating surface 48 of the plunger 47 until the throttle valve 55 is rotated to move the groove 57 out of registry with the passage 54 and to place the passage 58 in a position to communicate the passage 54 with the exhaust port 59 for exhausting pressure fluid from the bore 46. The spring 44

will then drive the riveting machine 20 rearwardly to its initial position and release the rocker bar and thus also the valve stem 80.

The spring 79 will then return the throttle valve 76 to its seat and at the same time the exhaust port 85 will be uncovered to permit the escape of the pressure fluid acting against the actuating surface 71. The valve 65 is then free to be moved into position for opening the portion of the supply passage 52 between the throttle valve 55 and the chamber 36 when the throttle valve 55 is again manipulated to supply pressure fluid to the chambers 46 and 36.

I claim:

1. A fluid actuated tool, comprising a casing having a pressure chamber and a supply passage for pressure fluid opening into the pressure chamber, means slidable in the casing having a pressure surface subjected to the pressure fluid in the pressure chamber, a pressure fluid actuated valve for controlling the supply passage, a throttle valve for controlling the supply of pressure fluid to the said fluid actuated valve, and a valve lifter actuated by the first mentioned means during movement thereof in the casing for actuating said throttle valve in one direction.

2. A fluid actuated tool, comprising a casing having a pressure chamber and a pressure fluid supply passage opening into the pressure chamber, means slidable in the pressure chamber having a pressure surface subjected to pressure fluid in the pressure chamber, a pressure fluid actuated valve for controlling the supply passage, a throttle valve for controlling the supply of pressure fluid to the said fluid actuated valve, and a valve lifter actuated by the first said means during movement thereof in the casing for actuating the throttle valve to a position for valving pressure fluid to the fluid actuated valve.

3. A fluid actuated tool, comprising a casing having a pressure chamber and a pressure fluid supply passage opening into the pressure chamber, means slidable in the pressure chamber having a pressure surface subjected to pressure fluid in the pressure chamber, a valve chamber in the casing, a fluid actuated valve in the valve chamber for controlling the supply passage having opposed differential actuating surfaces, the smaller 10 actuating surface being normally subjected to pressure fluid for holding the valve in position to permit the flow of pressure fluid to the pressure chamber, a throttle valve to valve pressure fluid to the actuating surface of larger area for moving the fluid actuated valve into position to cutoff the flow of pressure fluid to the pressure chamber, and a rocker bar actuated by the first said means during movement thereof in the casing for actuating the throttle valve.
- 20 4. A fluid actuated tool, comprising a casing having a pressure chamber and a pressure fluid supply passage opening into the pressure chamber, means slidable in the pressure chamber having a pressure surface subjected to pressure fluid in the pressure chamber, a valve chest having a valve chamber and inlet and exhaust ports for the valve chamber, a valve in the valve chamber having opposed differential actuating surfaces the smaller of which is normally subjected to pressure fluid for holding the valve in position to permit the flow of pressure fluid to the pressure chamber, a throttle valve to valve pressure fluid through the inlet port to the actuating surface of larger area and having means to control the flow 30 of such pressure fluid through the exhaust port, and a rocker bar extending into the path of movement of the first said means and actuated thereby to unseat the throttle valve.
